[57] CLAIM

The ornamental design for a kitchen utensil handle, as shown and described.

DESCRIPTION

FIG. 1 is a perspective view of a kitchen utensil handle
showing my new design;
FIG. 2 is a front elevation view thereof, the opposite side being identical;
FIG. 3 is a top plan view thereof, the opposite side
being identical;
FIG. 4 is a left side elevation view thereof; and,
FIG. 5 is a right side elevation view thereof.
